UNITED STATES PATENT OFFICE.

JOHN BOYD AND THOMAS A. BOYD, OF GLASGOW, COUNTY OF LANARK, SCOTLAND.

STOP-MOTION MECHANISM FOR DOUBLING, TWISTING, AND WINDING MACHINES.

SPECIFICATION forming part of Letters Patent No. 268,178, dated November 28, 1882.

Application filed October 27, 1881. (No model.)

To all whom it may concern:

Be it known that we, JOHN BOYD and THOMAS ALEXANDER BOYD, of Glasgow, of Lanarkshire, in the Kingdom of Great Britain and Ireland, have invented a new and useful Improvement in Stop-Motion Mechanism for Doubling, Twisting, and Winding Machines, of which the following is a specification.

Our invention relates to stop-motions for twisting and winding and other machines of analogous character; and it consists of improvements in the details of construction of the machinery described in United States Letters Patent granted to John Boyd, June 7, 1881, and July 19, 1881.

In the accompanying drawings, Figure 1, Sheet 1, is a vertical section of a spinning, twisting, and winding machine, showing our improvements on opposite sides of the machine, the devices on the left-hand side being shown as when the spinning is in progress, while those on the right are shown as when a thread is broken and spinning stopped. Fig. 2, Sheet 2, is an enlarged detached view of our improved stop-motion; Fig. 3, a detached view of the stop-rod; Fig. 4, an enlarged plan view on the line *a b*, Fig. 2, of the balance-levers for the detectors, and the thread-guide and starting-lever on the stop-rod; Fig. 5, an enlarged sectional view on the line *c d*, Fig. 2; Fig. 6, an enlarged sectional plan on the line *e f*, Fig. 2, showing the weighted lever carrying the stopper-rod and the cord-clutching devices; Fig. 7, views of the detectors; Fig. 8, a plan view of the traverse-bar for the detector-levers, and Fig. 9 a view of a modified form of detector mechanism.

As the stop-motion devices on opposite sides of the machine shown in Fig. 1 are precisely alike, a description of one will apply to the other.

Instead of mounting the lever which supports the stopper-rod so as to overhang the driving-cord, as shown in the above-cited patents, the weighted lever 1, with its tightening-roller 2, Figs. 1, 2, and 6, is placed beneath the spindle-driving cord 3. The tightening-roller 2, from its position in the weighted end of the lever when working, tightens, guides, and takes the half-twist out of the cord 3. Again, when the weighted end of the lever 1 falls, a great amount of slack is given to the driving-cord 3, and the friction of the same on

the pulley O is reduced to a minimum. The weighted end of the lever has a deep groove 55 for the reception of the roller 2, which is fast on a steel spindle, 2', adapted to chilled bearings formed in the weighted end of the lever 1, which bearings are provided with recesses 2², to hold oil and oil-wick, Fig. 6. The lever 1 is pivoted on the spindle 4', fixed between the sides 4² of the bracket 4, and engages, by the spindle 5, fixed in the short end of the lever 1, in the lower jaw 6' of the vertical rod 6. Two grips, 6², are cast one on each side of the rod 6, being convenient for gripping the spindle-cord 3 on either side, with the other grip, 7, which can be fixed and adjusted at will on either side of the bracket 4. The grips 6², being in close proximity to the grip 7 on the bracket 4, will, by coming into contact with the said grip 7, keep the rod 6 from twisting round very far to either side, Fig. 6. Farther up on the rod 6 is a small adjustable bracket, 8', to which is jointed a lever, 8, carrying the thread-hook 8³, and adapted to be used as a starting-lever. The inner end, 8², of the starting-lever 8 catches on the under edge of the main top rail, 16, and when the rod 6 rises the front end of the starting-lever 8 is raised, which makes it convenient to remove the bobbin from the twist-spindle. Again, by depressing the starting-lever 8 through the short inner end, 8², acting on the edge of the rail 16, great power is obtained to depress the rod 6 against the counter-weight 1 to put the parts into working action.

On the arm 6³ of the rod 6 a bracket, 9', is fixed, Fig. 2, which sustains a counterbalanced lever, 9, having an adjustable helix-weight, 9², to give the requisite counter-weight. A projection, 9³, Figs. 4 and 5, on the arm 6³ keeps the inner end, 9⁴, of the balance-lever 9 at the proper distance from the cam 10.

Detectors 11, varying in number according to the number of strands which are being twisted into one thread or cord, are held in the traverse-bar 12, which has a reciprocating motion imparted to it by the ordinary traverse motion, as described, for instance, in the Patent No. 217,769, July 22, 1879. The object of this is to prevent the yarns wearing ruts on the feed-rollers, which would be the case if the detectors 11 were stationary. When any one of the detectors 11 falls on the wide plate 9⁵ of the lever 9, Figs. 2 and 4, it depresses the lat-

ter till it falls onto the rest 9⁶, Fig. 5, formed on the inner end of the arm 6³. The end 9⁴ of the lever 9, coming into the path of the cam 10, the latter presses it against the resistance 5 of a spring, 13, which connects the hooked ends of the arms 6³ of the rods 6 on each side of the machine. The rod 6 is thus pushed over until the catch-plate 14 on the rod 6 is disengaged from the catch-plate 15 on the main top 10 rail, 16, when the counter-weight 1 will raise the rod, and with it will raise the upper roller, P, clear of the feed-rollers N and stop the feed. At the same time the lever 1, falling, leaves the 15 cord 3 slack, so that the spindle C will cease to rotate.

In the modification, Fig. 9, detector-triggers 17¹ are pivoted to a carriage, 17, on the arm 6³ of the rod 6, the threads to be twisted being passed through hooks 17², carried upward from 20 the trigger 17¹, and when any strand breaks its detector is acted on in the same way by the cam 10 to disengage the catch-plates 14 and 15, as will be readily understood. The rod 6, when lifted, raises the detector-triggers or counter- 25 balanced lever clear of the revolving cam 10.

The plate 18 on top of the rod 6 is formed with projections 18¹ at each end, on which the top roller, P, rests when lifted, leaving a clear space for the threads which are being twisted, 30 and on one end of the plate 18 is a vertical-end, 18², Fig. 3, to keep adjacent rollers separate and in their own places.

The detectors 11, which are used in the traverse-bar 12, are made of thin flatsteel, as shown 35 in Fig. 7. Stoneware eyes 11¹ are held in a curl formed at one end, and two small stop-pins, 11², are fixed in proper position to prevent the detectors from being pulled out of the guide-plates 12¹ 12² 12³, Figs. 2 and 8, by the 40 strain of the threads, or falling too far down when an end breaks or fails. The guide-plates 12¹ on the top of the bar 12 are formed by cutting the requisite number of slits 12² in one edge at respective distances immediately above 45 the plate 9⁵ of the balance-lever 9, on which they are to act. Corresponding wider slits, 12⁶, Fig. 2, are also formed in the traverse-bar 12, and the plate 12³ on the under side of the bar has also slits for the detectors. A second parallel plate, 12², on the top of the bar 12 is made 50 to swing forward on links 12⁴, Fig. 8, so that it can be moved back from the plate 12¹ to permit the taking out or putting in of detectors, as may be required. This swinging plate 12² is made to act for one or more adjacent sets of detectors in the length of a machine, and is held in position, when closed, by a pin, 12⁷. The plate 12³ on the under side of the bar 12, Fig. 2, is made by preference with slits wide 55 at each end and narrow in the center.

The cam 10 and feed-rollers may have rotary motion imparted to them from the shaft of the pulley O in any suitable manner, although we prefer the arrangement of gearing 60 shown by dotted lines in Fig. 1, and which will be readily understood without further explanation.

We claim as our invention—

1. The combination of the driving-cord, rod 6, catches for retaining the latter, and devices, substantially as described, for releasing the rod from the said catches, with a weighted lever supporting said rod, and carrying a roller at its weighted end adapted to bear on the under side of the driving-cord, all substantially 70 as set forth.

2. The combination of the frame, spinning-spindle, a rod, 6, and devices, substantially as described, for stopping said spindle, with a lever, 8, pivoted to said rod, and having an 80 arm bearing on a portion of the frame, whereby the said lever may operate the rod to throw the spindle into operation, all substantially as specified.

3. The combination of the frame, feed-rollers, and rod 6, carrying one of the feed-rollers 85 for the thread, with a lever, 8, pivoted to said rod 6, and having an arm bearing on a portion of the frame, whereby the said lever may operate the rod to bring the feed-rollers into contact, substantially as described.

4. The combination of the frame, a rod, 6, catches for said rod, and devices, substantially as described, for releasing it from said catches, with a lever, 8, pivoted to said rod, and carrying the front thread-guide and bearing on a portion of the frame, as and for the purpose set forth.

5. The combination of the frame, a movable rod, 6, having an arm, 6³, and detector-levers 90 mounted on said arm, with catches for retaining said rod, and a cam and operating mechanism for releasing the rod from the catches when the detector-lever falls, substantially as set forth.

6. The combination of the frame, a weighted lever, 1, movable rod 6, having an arm 6³, and detector-levers pivoted thereto, and retaining-catches for the rod, with a revolving cam, 10, adapted to act on the end of a detector-lever 110 when a thread breaks and release the rod, substantially as set forth.

7. The stop-rod 6, having at its upper end a plate, with projections 18¹ and a vertical end, 18², substantially as specified.

8. The combination of detector-levers, a traverse-bar, and operating mechanism, with detectors mounted in said traverse-bar, substantially as described.

9. A detector consisting of a strip of metal 120 having a stoneware eye at one end and stop-pins formed on the side, substantially as set forth.

10. The combination of a bar, 12, and slit guide-plates 12¹, with detectors and retaining-strip 12², substantially as set forth.

In testimony whereof we have signed our names to this specification in the presence of two subscribing witnesses.
